UNITED STATES PATENT OFFICE.

LEON TULEIKIS AND JOSEPH COLLINS, OF PHILADELPHIA, PENNSYLVANIA.

WINDOW CONSTRUCTION.

Application filed January 7, 1927. Serial No. 159,673.

Our invention relates to new and useful improvements in a window construction, and has for its primary object the provision of means to permit of swinging the lower or both sash inward relative to a building of which they form a part on a horizontal line whereby the outer surfaces of said sash will be accessible from the inside of the building.

Another object of the invention is to provide hinged window weight box portions with their associated sash guides so that said box portions may be swung outward from the window frame to permit access to both sides of one or both sash from one side of the window frame.

The invention consists essentially of dividing the upper portions of the sash weight boxes from the lower portions thereof and hinging the frame to the latter so that said upper portions may be swung out of the window frame, carrying with them whatever number of sash may be within said upper portions. It is to be specifically understood that the upper portions of the weight boxes as a whole are hinged to the lower portions for the purposes set forth in contra-distinction to the structure illustrated and described in our companion case filed on even date herewith.

With these and other ends in view, this invention consists in the details of construction and combination of elements herein-after set forth and then specifically designated by the claims.

In order that those skilled in the art to which this invention appertains, may understand how to make and use the same, we will describe its construction in detail, referring by numerals to the accompanying drawings forming a part of this application, in which:

Fig. 1, is a front elevation of a window and its component parts constructed in accordance with our invention, all the parts being shown in their closed positions.

Fig. 2, is a perspective view thereof with both sash in the upper portion of the sash weight boxes, and said portions swung out of the window frame, or inward relative to a building, so that access may be readily had to the outer surface of the window.

Fig. 3, is an enlarged sectional view at the line 3—3 of Fig. 1 with the upper portions of the boxes shown in an open position and both sash therein.

Fig. 4, is a view similar to Fig. 3 showing the upper sash in the lower portions of the boxes, and the lower sash in the upper portions of the boxes which are in an open position.

In carrying out our invention as herein embodied, 5 represents the usual window frame mounted in the wall of a building, parts of which are indicated by the numeral 6, and in the lower portion of this frame are mounted the lower portions 7 of the sash weight boxes, said portions being secured to the frame in any suitable or well-known manner, while to the upper ends of said lower portions 7 are hinged the upper portions 8 of the window sash boxes, said hinges being shown at 9. On the surfaces facing each other of both the upper and lower portions of the sash weight boxes are mounted beads or strips 10 in spaced relation to provide guideways for both sash, the lower one being indicated by the numeral 11, and the upper one by the numeral 12.

It might be well to mention at this time that usually the lower sash is longer than the upper one, and under such conditions, it is necessary to hinge the sash weight boxes at such points if the upper portions thereof are of sufficient length to receive the lower or longer sash.

Both sash are weighted as usual, and as herein illustrated the lower sash 11 has sash cords 14 connected to it and to weights 15, said cords running over the usual pulleys 16, in the upper ends of the sash weight boxes and through openings in the walls of said boxes, while the upper sash has sash cords 17 connected to it and to weights 18 in the boxes, said last-named cords also running over pulleys in the upper ends of the boxes, and through openings in the walls of said boxes. It is to be understood that the boxes are divided into two compartments by partitions 19 for separating the weights from each other.

In order to normally maintain the upper portions of the weight boxes in an upright closed position, spring actuated latches 20 are mounted on the upper ends of the upper portions, and when said upper portions are in a closed position, the bolts of the latches will be forced into and normally engage keepers 21 here shown as apertures in the window frame, but it is to be understood that said apertures might be surrounded by metal escutcheons.

For convenience of operating the latches, suitable actuating rods 22 are pivotally connected with the latch bolts, and said rods are of such length that they may be conveniently reached by persons who may desire to open the upper portions of the sash boxes. After the sash boxes have been opened, they may be supported in an inclined position by placing the lower ends of the actuating rods 22 in the lower part of the window frame and against the lower portions of the sash weight boxes, as plainly shown in Fig. 2.

When it is desired to clean the outer surfaces of the window panes or the exposed portions of the frame work of both sash, the lower window sash may be raised so that both sash are in the upper portions of the sash weight boxes, then by pulling upon the actuating rods 22, the bolts of the latches 20 will be withdrawn from their keepers, and said upper portions of the sash weight boxes opened because of their hinged connections with the lower portions of said boxes, as shown in Fig. 2, and said upper portions of the boxes with both sash therein may be supported in the inclined position by the rods 22. While in this position, the outer face of the upper window pane and the outer exposed surface of the window frame work may be cleaned, or other work done thereon, after which the upper portions of the sash weight boxes are returned to their closed positions, and the upper sash moved down into the lower portions of the weight boxes. The upper portions of the weight boxes are then again opened exposing the outer surface of the lower sash, so that it may be worked upon, the same as the upper sash. After the cleaning or other operations have been completed, the upper portions of the weight boxes are finally moved into their closed positions where they will be held by the spring latches 20, and both window sash may then be raised or lowered in the usual manner.

While it does not seem to be absolutely necessary, we believe it advisable to brace the outer free ends of the sash weight boxes by cross strips 23 to prevent said sash weight boxes from spreading apart.

When the upper portions of the sash weight boxes are moved into their open position, as shown in Fig. 2, the window sash may be readily removed therefrom by pulling said sash downward and loosening or unhooking the sash cords. Such an arrangement also makes it easy to replace worn or broken sash cords with new ones. In order to prevent accidental sliding of the sash from the sash weight boxes, a latch 24 may be placed on one side of each sash so as to engage the sash weight box portions, thus securely locking the sash in place.

By providing a window construction as herein described, the outer surfaces of both

window sash may be readily exposed, one at a time within the building, thereby eliminating the necessity of sitting on a window sill or using a support on the outside of the building to clean or do any other work upon the outer surface of either window sash.

It will be readily noticeable that the actuating rods 22 may be used for supporting curtains, draperies or other objects, making it unnecessary to use the ordinary curtain rods or brackets.

Where it is desirable to use separate curtain or shade brackets these may be properly positioned under the spring actuated latches 20 at right angles to said latches.

Of course we do not wish to be limited to the exact details of construction as herein shown as these may be varied within the limits of the appended claims without departing from the spirit of our invention.

Having thus fully described our invention, what we claim as new and useful is:

1. A window construction including sash weight boxes, between which sash are mounted for sliding movement, said weight boxes including upper and lower portions hinged together.

2. A window construction comprising upper and lower sash weight box portions hinged together at their meeting ends, whereby said upper portions may be swung into or out of endwise alignment, and window sash slidably mounted between said boxes, and adapted to be moved with the upper portions of the boxes when in said upper portions.

3. The structure set forth in claim 2 in combination with the window frame in which the boxes are set, with the lower portions thereof in fixed position, and means to temporarily hold the upper portions of the weight boxes within the frame.

4. A window construction comprising a pair of two-piece sash boxes arranged in parallelism, and means to hinge the upper portions of said boxes to the lower portions thereof, whereby said upper portions may be swung out of endwise alignment with the lower portions while remaining parallel with each other.

5. A window construction comprising a window frame, lower portions of sash weight boxes fixed within the frame, upper portions of sash weight boxes hinged to the upper ends of the lower portions thereof so as to swing relative to said lower portions, while remaining parallel to each other, weighted sash slidably mounted between the weight boxes and adapted when in the upper portions of the weight boxes to be moved therewith, and means to temporarily maintain the upper portions of the weight boxes within the window frame.

6. The structure set forth in claim 5 wherein the means for holding the upper

portions of the weight boxes within the window frame consists of spring actuated latches and actuating rods connected with said latches and depending to a position within easy access of an operator, said rods 5 engaging the lower portions of the weight boxes and the window frame to hold the upper portions of the weight boxes in an inclined position.

10 7. A window construction comprising a window frame, lower portions of sash weight boxes fixed within the lower part of the window frame, upper portions of sash weight boxes, means to hinge the lower 15 ends of the upper portions to the upper ends of the lower portions whereby said upper portions may be swung into or out of the window frame parallel with each other, guideways on the surfaces of the boxes facing each other, window sash slidably 20 mounted in said guidways, and when within the confines of the upper portions of the weight boxes to be moved therewith, pulleys adjacent the upper ends of the upper portions 25 of the weight boxes, sash cords connected with the sash and passing over the pulleys into the boxes, weights on the ends of the cords within the boxes, spring actuated latches mounted on the upper ends of 30 the weight boxes, the bolts of said latches adapted to register with the keeper recesses in the window frame, and actuating rods for operating said latches and said rods 35 engaging the lower parts of the weight boxes and window frame when the upper portions of said boxes are opened in order

to support said upper portions in inclined positions.

8. The structure set forth in claim 7 wherein the upper portions of the sash 40 weight boxes are of a length equal to at least the length of the longer sash regardless of the length of the lower portions of the weight boxes.

9. A window construction including sash 45 weight boxes between which sash are mounted for sliding movement, the said sash weight boxes including upper and lower portions, means to hinge the lower ends of the upper portions to the upper ends 50 of the lower portions, and cross strips fixed to the upper free ends of the upper portions to hold them in spaced relation.

10. A window construction comprising upper and lower sash weight box portions 55 hinged together at their meeting ends whereby said upper portions may be swung into or out of endwise alignment with the lower portions, means to hold the upper free ends of the upper portions in spaced 60 relation, window sash slidably mounted between said sash weight boxes and adapted to be moved with the upper portions of said boxes when in said upper portions, and latches carried by the sash and engaging 65 the sash weight box portions to prevent accidental displacement of the sash.

In testimony whereof, we have hereunto affixed our signatures.

LEON TULEIKIS.
JOSEPH COLLINS.
